UNITED STATES PATENT OFFICE.

FREDERICK W. VODOZ, OF CHICAGO, ILLINOIS.

MANGLE OR IRONING MACHINE.

Application filed September 25, 1920. Serial No. 412,825.

To all whom it may concern:

Be it known that I, FREDERICK W. VODOZ, a citizen of the United States, residing at Chicago, in the county of Cook and State of Illinois, have invented a Mangle or Ironing Machine, of which the following is a specification.

This invention relates to improvements in mangles, or ironing machines, and has for its principal object to provide an improved construction of machines of the class described. Other objects and features of my invention will appear as the description proceeds.

15 The invention consists in the construction, combination, and arrangement of parts, as are described in the following specification, in connection with the accompanying drawings, and more specifically pointed out in the appended claims.

In the drawings, Fig. 1 is a side view of a machine embodying my invention, with the heating element in one position.

25 Fig. 2 is a front view of the machine, with the heating element in the position shown in Fig. 1.

Fig. 3 is a side view, with the heating element in a second position.

In the embodiment of my invention illustrated herewith, a frame A, comprises side supporting members 10, 10, a pair of longitudinally disposed cross members 11, 11^a, spaced apart and adjacent the top of said side members, and other suitably disposed cross members 12. The cross members 11, 11^a, and 12, preferably comprise tubular bars or rods, mounted in suitable brackets 11^b, 11^b attached to side supports 10, 10. The frame is mounted on casters 13, 13, each having a shank 13^a mounted to turn in a sleeve 13^b mounted on the frame, and provided with a ball bearing 13^c interposed between the upper end of said shank and a cap screw 13^d, threaded in the upper end of said sleeve and adapted to be readily adjusted so as to regulate the height of the caster when the machine is used on uneven floor surfaces.

An ironing roller 14 is mounted above and longitudinally of the frame A, and is supported at one end by a bearing bracket 15, and at the other end by a worm gear housing 16, the two last mentioned members both being mounted on the cross members 11, 11^a, by means of sleeves 17, 17, and 18, 18, ar-

ranged to be movably adjusted therealong, in order to provide easy assembly and disassembly of the roller, and to permit the use of rollers of varying lengths, as desired. The bearing bracket 15 is preferably provided with a hollow end portion 15^a, suitable for containing grease or other lubricant, and having annular ball bearings 15^b of any approved pattern, retained in place by a packing gland 15^c, suitably secured to the bracket 15 to provide an oil-proof bearing for the roller shaft 15^d. The bearing construction for the opposite end of the roller is similarly designed, and comprises roller bearing 16^a, and packing gland 16^b mounted on the housing 16, about the shaft 16^c. A worm gear 16^d is also carried on the said shaft 16^c within the said housing, the latter being split on a horizontal plane, as shown in Fig. 1, to afford access to the mechanism therein.

A work table 20 is provided on the front, or advance side of the machine, and comprises a horizontal board 21, having its inner margin adjacent the roller 14, and supported by forked brackets 22, 22, which rest on the front cross bar 11, and hinged links 23, 23, which connect the outer margin of the table to the frame. This arrangement allows the table to be folded downwardly, for compactness in shipping, when desired.

A folding hopper 24 is also hinged to the front of the frame, and supported by links 25, 25, attached to links 23, 23. The hopper is adapted for holding the work before it is placed in the mangle.

A receiving table 26 is provided at the rear of the machine, and may be constructed similarly to the front table 20, excepting that it is preferably arranged somewhat lower, as shown. In addition, the receiving table is arranged so that it may be swung to a second position, shown in dotted lines in Fig. 1, in which the supporting links 27, 27, are swung about the pivots 27^a, 27^a, and the forked brackets 28, 28, engage with a cross member 28^a, to hold the table in substantially horizontal position, as shown. The purpose of this arrangement is to allow a larger "drop" for pieces of large dimensions as they are passed thru the machine, thereby facilitating the ironing and folding of pieces such as sheets and the like.

A plurality of fingers 29, 29 are arranged

along a member 29^a carried by the frame, adjacent the receiving table 26, said fingers being resilient, and preferably of non-corrosive material, such as brass, and adapted 5 to contact with the roller to pick off pieces of work which may tend to adhere thereto.

The mechanism for applying heat to the work comprises a heating element 30, extending substantially the length of and 10 above the roller 14, and having a curved heating-plate 31, or "hot plate" conforming substantially with the shape of the roller. The element 30 may be heated by any suitable means, such as gas, or electricity, but 15 in the embodiment illustrated, I have shown a gas-heated device, comprising a hood 32, and a gas burner 33 of an approved pattern, extending the length of the hot plate 31. End-plates 34 and 35 are provided at the 20 respective ends of the heating element, on which the burner 33 is supported. A pair of laterally extending brackets 34^a and 35^a are connected with the end plates 34 and 35, respectively, and connect with vertically dis- 25 posed supporting arms 36 and 37, respectively. The heating element is preferably mounted on said arms by means of resilient connections 38, 38, each comprising a casting 38^a attached to the upper end of said 30 arms, and having a vertically disposed pin 38^b extending through each of the brackets 34^a and 35^a and connected thereto by a spring 40 mounted on the upper end of said pin 38^b and connected with an adjustable 35 wing nut 39, to regulate the tension of the heating element upon the roller.

The gas burner 33 is fed by a suitable pipe 41, preferably supported by the adjacent casting 38^a and having a valve 42 of 40 any suitable type, adapted to be controlled by a lever 43, as will be more fully described. The lower ends 44, 44 of the supporting arms 36, 37, are connected together by a cross member 45. A pair of suitable lugs 45, 46, are carried by said arms and move in vertically disposed guides 47, 47, attached to the side members 10, 10, as shown. A pair of rocking links 48, 48 are also connected to said arms, and pivoted to the 50 frame, preferably on the rear cross-bar 11^a thereof. The arrangement is such that the heating element 30, supporting arms 36 and 37, and cross-bar 45 are movable as a unit, which movement is controlled by the links 55 48, 48, and guides 47, 47, so as to displace the heating element 30 rearwardly with respect to the roller 14 as it is raised therefrom, in the position shown in Fig. 3. The purpose of this arrangement is to provide 60 an unobstructed upper surface of the roller so that work may be placed thereon in position for beginning the ironing operation. The mechanism for actuating the heating element and associated parts just described 65 comprises a foot-lever or treadle 49, pivoted

on the cross-bar 45, and having an upwardly extending arm 49^a forming one member of a toggle device. The other member of said toggle device is a bell crank lever 50, having one arm 51 connected at one end to the 70 arm 49^a of the treadle, and the other end pivotally connected to the frame, preferably on the front cross bar 11, as shown. A spring 52, or similar tension device, is provided to exert a tension on the bar 45 toward the opposite point of connection of the toggle device, which in the construction illustrated is the bar 11, as above described. The toggle device is also provided with a suitable stop, as for instance an offset portion 53 of the toggle joint 53^a, which limits the relative movement of the levers to form a locked relation thereof, when they are moved slightly beyond alignment with each other, and the heating element is in engagement with the roller, as illustrated in Figs. 1 and 2. The toggle is unlocked, or "broken", by means of a second arm 51^a 80 preferably made integral with the lever 50, and extending forwardly from the machine in position to be manipulated by the operator.

Mechanism for actuating the roller 14 comprises a worm (not shown) meshed with the worm gear 16^a in the gear housing 16, as already described, and driven by a suitable electric motor 54 mounted on the frame. Electrical connections for the motor comprise a socket plug 55, including a switch of the usual type operated by a pull cord 56. Said pull cord is attached to a rocking arm 57 pivotally connected to the frame, and adapted to be actuated by a cam 58 mounted on the arm 37. By means of the arrangement just described, the motor is automatically started by opening the supply circuit to the driving motor when the heating element is brought into contact with the roller, and immediately stopped again as the heating element is withdrawn. The switch 55 may also be independently actuated by the operator, by means of the control rod 55^a, attached to the arm 57.

An automatic control for the heating device comprises the valve 42 for controlling the gas supply to the hot plate, and a control lever 43 of said valve, adapted to coact with a part 59 fixed on the machine frame so as to be automatically opened a desired amount as the heating element is lowered into operating position on the roller, and diminished when the heating element is raised. A preferred device for controlling the said valve comprises a V-shaped slot in the lever 43, which will allow the valve 42 to be manually opened when the heating element 30 is in the raised position shown in Fig. 3, and it is desired to heat the hot plate 31 preparatory to use, but which will automatically control the valve so as to open it 115 120 125 130

when the hot plate is brought into contact with the roller, and close it when the hot plate is raised.

The use and operation of my invention is 5 as follows:

The heating element 30 is normally held in its raised position by the tension device 52, as illustrated in Fig. 3, in which it is thrown rearwardly away from the roller to 10 leave the latter unobstructed for placing work thereon. In this position, the control lever 43 is in the position indicated in full lines in Fig. 3, in which position the valve 42 is partially closed. When it is desired 15 to heat the hot plate 31, preliminary to the use of the machine, the lever 43 may be fully opened, either by manually moving lever 43 to opened position, as indicated in dotted lines in Fig. 3, or, if preferred, by pressing 20 the treadle downwardly to lower the heating element into position shown in Fig. 1, in which case the valve 42 will automatically be opened, as shown. When the hot plate has been heated to the desired degree, the 25 mechanism is then moved to the position shown in Fig. 3, and the machine is now ready for operation. The work is placed along the roller 14, and the treadle 49 is depressed by the operator, bringing the hot 30 plate into contact with the work and simultaneously starting rotation of the roller by turning on the current to the driving motor 54 at switch plug 55 by means of the cam device 57 before described. The roller thus 35 starts to revolve, and the work is carried under the hot plate and deposited on the receiving table 26. It will be noted, that the toggle levers 49^a and 51 become locked when the heating element is brought into 40 contact with the roller, so that after the treadle 49 is once depressed, the pressure may be removed therefrom, and the ironing operation may continue until it is again desired to lift the heating element. This is 45 accomplished by depressing the lever 51^a, which unlocks, or "breaks" the toggle, and allows the heating element to be raised by the spring 52. As the heating element is raised, the driving motor and roller are 50 stopped by action of the cam 58 and switch 55, and similarly, the gas supply is diminished by movement of the lever 43, which 55 partially closes the valve 42 to such a degree that the hot plate will not be heated to a dangerous degree in case the machine is not used for a relatively short time, yet will be sufficiently heated for subsequent use, as desired.

In the event that relatively large pieces, 60 such as sheets or the like, are to be ironed, the receiving table may be moved to a lower position, so as to facilitate the handling of such work, as already suggested.

Among novel features of construction 65 not already pointed out, is the means

whereby the power is applied approximately at the center of the cross-rod 45 associated with the heating element 30. This construction affords an equalization of pressure of the heating element on work of uneven 70 thicknesses when applied to opposite ends of the roller.

It will be understood that I have shown and described simply one form of my invention, and in doing so, have set forth certain 75 parts and relations thereof, but I wish it to be understood that I do not thereby desire to limit myself to these particular forms nor to this particular embodiment of my invention, excepting as specifically limited in the 80 following claims:

I claim:

1. In an ironing machine, the combination of a frame, a roller mounted thereon, a coacting shoe, a movable support for said shoe, means on said frame for controlling the movement of said support in a vertical plane comprising a pivoted link and a vertically disposed guide, and means for actuating 85 said support. 90

2. In an ironing machine, the combination of a frame, a roller mounted on said frame, a shoe coacting with said roller, supporting arms connected with said shoe, a member connecting said supports together, and means for controlling the movement of said supporting members, comprising guides fixed to said frame and links pivotally connecting said arms to said frame, and a foot 95 operated member for exerting pressure on 100 said connecting member. 105

3. In an ironing machine, the combination of a frame, a roller mounted on said frame, a shoe coacting with said roller, means for movably supporting said shoe, comprising endwise shiftable arms connected to the ends of said shoe, and a transverse connecting member connecting the opposite ends of said arms, vertical guides mounted on said frame and engaging said arms, a treadle mounted 110 on said connecting member for depressing said shoe, toggle mechanism for holding said shoe in depressed position, and a spring 115 acting to elevate said shoe when said toggle mechanism is flexed. 120

4. In an ironing machine, the combination of a frame, a roller mounted on said frame, a shoe coacting with said roller and comprising vertical supporting arms extending downward from the ends of said shoe, and 125 mounted for endwise sliding movement on said frame, means for depressing said supporting arms, toggle members actuated by said depressing means for locking said arms in depressed position, and a foot operated lever connected with said toggle for releasing said arms from depressed position. 130

5. In an ironing machine, the combination of a frame, a roller mounted on said frame, a shoe coacting with said roller and compris-

- ing vertical supporting arms extending downward from the ends of said shoe, and mounted for endwise sliding movement on said frame, a foot operated lever connected with said arms for depressing the same, toggle members operative by said lever for retaining said arms in depressed position, and another lever for breaking said toggle members to release said arms.
6. In an ironing machine, the combination of a frame, a roller, a shoe coacting with said roller, arms supporting the ends of said shoe and having endwise sliding engagement with said frame, links pivotally connecting said arms with said frame, a lever operatively connected with said arms for shifting said shoe in working contact with said roller, said link acting to simultaneously shift said shoe through a predetermined angle relative to the circumference of said roller, and foot pressed means for retaining said shoe in working contact with said roller.
7. In an ironing machine, the combination of a frame, a roller, a shoe coacting with said roller, arms supporting the ends of said shoe and having endwise sliding engagement with said frame, intermediate the ends of said arms, a rod connecting the lower ends of said arms, a foot lever mounted on said rod intermediate its ends, and forming one member of a toggle mechanism, the other member being pivotally connected to said frame, and an auxiliary foot lever connected to said last mentioned toggle member, for breaking said toggle.
8. In an ironing machine, the combination of a frame, a roller mounted on said frame, a shoe adapted to be moved into and out of working contact with said roller, shoe supporting arms having endwise sliding connection with said frame, a foot operated lever connected with said arms, for moving said shoe into working contact with said roller, a spring acting to move said shoe out of working contact, and toggle mechanism operatively connected with said foot lever, and adapted to hold said arms against the tension of said spring, and comprising a foot lever for releasing said toggle mechanism.
9. In an ironing machine, the combination of a frame, two coacting ironing members, a movable unit supporting one of said members, and slidably connected with said frame, a tension member acting to shift said unit in one direction, a lever for shifting said unit in the opposite direction, toggle levers operatively connected with said lever for holding said unit against the action of said tension member, means for limiting the relative movement of said toggle levers in one direction to lock the same, and an auxiliary lever for releasing said toggle levers.
10. In an ironing machine, the combination of a frame, a roller mounted thereon, a movable shoe, supporting members connected with said shoe and extending downwardly therefrom, guides and links connecting said supports with said frame permitting upward and rearward displacement of the shoe, toggle mechanism interposed between said frame and the lower portions of said supports, and foot levers for actuating said toggle levers and releasing the same.
11. In an ironing machine, a frame, a roller mounted thereon, a pressing member comprising a coacting shoe, and a support therefor adapted for pivotal and vertical movement on said frame, whereby said shoe may be displaced upwardly and rearwardly of said roller, and means for actuating said support, comprising toggle mechanism interposed between said frame and said support, and a foot lever connected with said toggle mechanism.
12. In an ironing machine, two coacting members, one of which is movable, means for heating one of said members adapted to be automatically controlled by relative movement of said members, including a movable lever arm mounted on one of said members and having slidable engagement with a fixed part on the other of said members, and means permitting manual movement of said lever arm in one relative position of the movable members.
13. In an ironing machine, two coacting members, one of which is movable, means for heating one of said members having means automatically controlled by relative movement of said members, said controlling means including a movable lever having a forked arm mounted on one of said members and normally actuated by sliding engagement with a fixed part on the other of said members, said arm being manually movable independent of said automatic controlling means when said movable members are withdrawn from each other, but automatically re-engageable with said controlling means upon further co-operative action of said movable members.

FREDERICK W. VODOZ.
